Primary Examiner — John Windmuller*Assistant Examiner* — John R Yeh(74) Attorney, Agent, or Firm — Daniel J. Iden(57) CLAIM

The ornamental design for a floor scrubbing pad, as shown and described.

DESCRIPTION

The patent or application file contains at least one drawing executed in color. Copies of this patent or patent application publication with color drawing(s) will be provided by the Office upon request and payment of the necessary fee.

FIG. 1 is a color photograph of a perspective view of a floor scrubbing pad showing the new design;

FIG. 2 is a top view thereof;

FIG. 3 is a front view thereof, the rear view being a mirror image of the front view shown;

FIG. 4 is a left side view thereof, the right side view being a mirror image of the left side view shown; and,

FIG. 5 is a bottom view thereof.

1 Claim, 2 Drawing Sheets
(2 of 2 Drawing Sheet(s) Filed in Color)
